UNITED STATES PATENT OFFICE

BENJAMIN MINTZ, OF BROOKLYN, NEW YORK

DESIGN FOR A TEMPLE FOR SPECTACLES OR THE LIKE

Application filed January 16, 1932. Serial No. 42,512. Term of patent 7 years.

To all whom it may concern:

Be it known that I, BENJAMIN MINTZ, a citizen of the United States, residing at Brooklyn, New York, in the county of Kings, and State of New York, have invented a new, original, and ornamental Design for a Temple for Spectacles or the like, of which the following is a specification, reference being had to the accompanying drawings, forming part thereof.

Fig. 1 is a side elevational view of a temple for spectacles or the like, showing my new design.

Fig. 2 is a plan view of the same.

Fig. 3 is an inner side view of the same.

I claim:

The ornamental design for a temple for spectacles or the like, as shown.

In testimony whereof I have affixed my signature.

BENJAMIN MINTZ.
